UNITED STATES PATENT OFFICE

1,991,925

CENTRIFUGAL CREAM TESTER

Ray H. Garver, Hiram, Ohio

Application October 8, 1931, Serial No. 567,747

2 Claims. (Cl. 233—26)

This invention relates to improvements in that type of centrifugal cream testers commercially known as Babcock testers, and has as its primary object improvements in details of construction and mode of operation and control.

A more detailed object is the provision for maximum capacity in a minimum space by apparatus involving a minimum cost of production.

With these and other objects in view as will hereinafter in part become apparent and in part be stated, the invention includes a centrifuge of star wheel contour having test cup supports at the points of the star, and also includes a motor mounted to be surrounded by the test cups when pendent, the motor being located between the centrifuge and the base of the container in which the centrifuge is mounted.

Other features and details of the invention will become apparent hereinafter and be subsequently 20 specifically pointed out in the appended claims.

In the accompanying drawings,—

Figure 1 is a sectional elevation of a cream tester embodying the features of the present invention.

Figure 2 is a top plan view thereof.

Figure 3 is an enlarged, fragmentary, vertical section through the motor and adjacent parts, parts being seen in elevation and parts being broken away for the saving of space.

Referring to the drawings by numerals, 1 indicates a bowl or other container, preferably of metal, such as aluminum, having a detachable cover 2. The cover 2, for convenience and facility of operation and observation of the action 30 of the apparatus, is preferably made of two parts hinged together at 3, 3, the smaller of the two parts being provided with an appropriate operating handle or knob 4 to facilitate manual opening and closing when desired. The pendent 40 flange of the lid or cover 2 is preferably continuous, as seen in Figure 1, and the flange of the smaller section of the cover having the knob 4 overhangs the extended portion of the flange of the other part of the cover, so that the cover 45 is frictionally retained on the rim or collar of the bowl 1 against accidental dislocation. The entire cover, however, is adapted to be removed when desired, and to facilitate such operation, an appropriate knob or handle 5 is preferably 50 fixed to the cover at the central point thereof. A preferably electrical heating unit 6 is carried by the cover 2, preferably centrally at its under surface, for facilitating raising and maintaining the temperature within the bowl 1 at any given desired degree.

Bowl 1 is mounted on an appropriate stand or base 7, and to that end the bowl 1 is preferably provided with spaced feet or lugs 8, 8, three such feet 8 being sufficient and the usual number employed, but a greater number may be provided if desired. 5

The bottom of the bowl 1 is preferably provided with a central opening, and upstanding through the said opening is the housing 9 of an electric motor made up of field laminations and coils 10, and armature 11 carried by the shaft 12, which in turn sustains and actuates the star-shaped centrifuge 13. The shaft 12 is provided with appropriate vertical bearings in the housing 9, and a stepped bearing 14 at the lower end of the shaft. The stepped bearing preferably consists of a ball mounted in a parti-globular recess in the upper end of an adjusting pin 15 threaded upwardly through the lower wall of housing 9 and locked in place by a clamping nut 16. Housing 9 is preferably made up of a main shell and a removable cap 17 seated on the upper edge of the shell and preferably lapping such edge at 18 and retained in place by appropriate through bolts 19. 20

The centrifuge 13 is referred to as star-shaped because it is made up essentially of a plate so serrated marginally as to produce a series of radiating points 20, 20, as clearly seen in Figure 2. Each of said points is, in fact, an outstanding, upwardly-curved arm, as best seen in Figure 3, and as a means of stabilizing each of said arms an appropriate fillet 21 extends along the arm, is preferably formed integral therewith, and is also preferably formed integral with the plate 3. Each arm making up a point of the star is provided with trunnion lugs 22 extending transversely of the respective arm and outstanding at the two sides thereof to receive the usual bails 23 of the test cups 24, there being preferably one test cup 24 arranged between each pair of two adjacent arms of the centrifuge 13. While, for clearness of disclosure, only a single cup is illustrated, it will be understood that the apparatus involves a set of cups equal to the number of serrations represented by the spaces between the star arms just described. The cups hang pendent when the apparatus is not in operation, swinging from the trunnions 22 and pivoting about said trunnions as the cups 24 swing outward to an outstanding radial or horizontal position when the motor is in operation and the centrifuge 13 is revolving at sufficient velocity. 30

The motor is constructed to consume a relatively moderate starting current and has a re- 55

sultant moderate torque which is particularly adapted to this type of apparatus for efficient operation and preventing such defects as arise from too sudden acceleration. The loss and injury likely to flow from too sudden acceleration would, of course, be liable to occur with too sudden deceleration. Naturally, the time element frequently is an important factor, and if the stopping of the apparatus is to depend upon mere cutting off of power, the momentum will represent a substantial delay in having the apparatus come to a standstill, but, on the other hand, just as the motor in its construction provides for a slow and gradual start, provision is here made for a slow and gradual stop while more rapid than the stop that would occur incident to mere loss of momentum. To this end, a brake is provided to effect as rapid slowing down of the centrifuge 13 as may be practicable without danger of injury from deceleration. The brake, while susceptible of assuming various forms, consists preferably of a vertically reciprocating rod 27 extending through the housing 9 as a guide, the rod having appropriate slide bearings in the walls of the housing 9. Fixed to and carried by the upper end portion of rod 27 is a horizontal plate 28, preferably in the form of a disc, but obviously susceptible of having any of various contours. Fixed to the upper face of the plate 28 is an appropriate brake lining 29 disposed to be lifted to contact with the under surface of the plate making up the centrifuge 13. The brake is preferably located spaced as far from the axis of rotation of the centrifuge as practicable while enabling the brake lining 29 to uniformly contact with an uninterrupted braking surface of the centrifuge 13. The rod 27 is preferably stressed by a spring 30 in a downward direction to prevent the brake lining 29 from contacting with the under surface of centrifuge 13 except when and as desired by the operator. The spring 30 is preferably located on the rod 27 between the bottom wall of housing 9 and the upper nut of a pair of clamping nuts 31, 31, carried by the lower end of the rod 27. An operating lever 32 extends through an opening in the base 7 and rests on the lower rim thereof, the outer portion of the lever 32 being bent to upstand sufficiently for purposes of operation, and the inner end portion of the lever 32 carrying a spring or other elastic extension 33 extending between and

clamped by the nuts 31. Thus, when the outer end portion of lever 32 is depressed, the lever will rock on the lower rim of base 7, so that its inner end will be elevated and cushioned pressure exerted on rod 27 upwardly sufficient to overcome the stress of spring 30. The brake 28 is thereby lifted until its friction surface 29 contacts with the braking surface of the under face of the centrifuge 13. The two springs 30 and 33 acting against each other facilitate cushioning and gradual taking hold by the friction surface of the brake, and thus the centrifuge is slowed down much more quickly than if left to come to a stop by loss of momentum, and yet no danger is occasioned of injury or loss from too sudden or rapid deceleration. The braking action is accomplished without jar or shock and with a smoothness comparable with natural loss of velocity except that the centrifuge is brought to a standstill much more quickly.

The housing 9 rests on the base 7 as does the bowl 1, and the housing 9 snugly fits in the opening in the bottom of bowl 1, but by preference a draining passage or opening 34 is provided through the bottom of the bowl to allow escape of such liquids as may be spilled within the bowl.

What is claimed is:—

1. In apparatus of the class described, the combination, with an electric motor housing having a recess, a field magnet seated in said recess, and an armature movable relative to and cooperating with said magnet, of a centrifuge plate connected to be actuated by said armature, a brake rod extending through the field magnet and serving to retain the same in said recess, a brake carried by the brake rod in position for engaging a surface of the centrifuge plate, and elastic means for applying and removing the brake with respect to said plate.

2. The combination of an electric motor having a housing, a centrifuge plate actuated by the motor, a brake rod extending through and guided by the housing, a brake carried by the brake rod in position for engaging the centrifuge plate, a spring for stressing the brake away from contact with the centrifuge plate, a lever for moving the brake into such contact, and cushioning means for transmitting movement from the lever to the brake.
